DESIGN FOR A BILLFOLD

Warner W. Hoople, Evanston, Ill., assignor to Euger-Kress Company, West Bend, Wis., a corporation of Wisconsin

Application October 18, 1940, Serial No. 95,917

Term of patent 7 years

To whom it may concern:

Be it known that I, Warner W. Hoople, a citizen of the United States, residing at Evanston, in the county of Cook and State of Illinois, have invented a new, original, and ornamental Design for a Billfold, of which the following is a specification, reference being had to the accompanying drawing, forming part thereof.

In the drawing:

fold in closed position showing my new design.

I claim:

The ornamental design for a billfold, as shown.

WARNER W. HOOPLE.
